UNITED STATES PATENT OFFICE.

JESSE M. BROWN, OF BOSTON, MASSACHUSETTS.

SHOE-HORN.

SPECIFICATION forming part of Letters Patent No. 267,668, dated November 21, 1882.

Application filed September 11, 1882. (No model.)

To all whom it may concern:

Be it known that I, JESSE M. BROWN, of Boston, county of Suffolk, State of Massachusetts, have invented an Improvement in Shoe-Horns, of which the following description, in connection with the accompanying drawings, is a specification.

My invention relates to a shoe-horn, and is embodied in a shoe-horn made in two portions, one adapted to slide telescopically within the other. One of the said portions is preferably provided with a heel-engaging hook to engage the upper edge of the heel of the shoe, and the other portion, when drawn out, projects above the heel of the shoe in such position as to receive the heel of the foot that is being inserted in the shoe, the said portion sliding down with the foot into the shoe, so that there is no friction between the shoe-horn and the stocking, the sliding motion taking place between the two portions of the horn. In addition to the increased convenience in using the said horn it occupies, when made in two portions, as described, much less space than the ordinary horn composed of a single piece, and can consequently be more conveniently carried in the pocket or in a traveling-bag.

Figure 1 shows in longitudinal section a shoe-horn embodying this invention applied to a shoe; Fig. 2, a transverse section of the said shoe-horn, and Fig. 3 a front elevation thereof.

The shoe-horn is composed of two parts, *a* *a'*, properly curved to fit the heel, as shown in Fig. 2, and the former arranged to slide longitudinally within the latter, which is curved over at its edges, as shown at 2, to form guides for the sliding portion *a*. The portion *a'*, which is intended to pass within the heel of the shoe, is bent over at its upper edge to form a heel-engaging hook, *b*, the said portion *a'* thus being suspended from the top of the heel rather than resting upon the sole at the lower end of the heel, as is usually the case. The portion *a* is preferably provided with a stop-projection, *c*, traveling in a groove, *d*, at the rear side of the portion *a'*, the said projection *c*, by its engagement with the shoulder 3, formed at the upper

end of the said groove *d*, preventing the portion *a* from being wholly withdrawn from the portion *a'*.

In using the shoe-horn the portion *a* is drawn out from the portion *a'*, the hook *b* of which is engaged with the heel of the shoe, as shown in Fig. 1, and in inserting the foot into the shoe the portion *a* will slide down with the foot into the portion *a'* in the shoe, after which the two portions *a* *a'* may be withdrawn together in the usual manner.

When not in use the portion *a* may be slid down into the portion *a'*, so that the entire shoe-horn will occupy scarcely more than half the space occupied by one of ordinary construction.

By making the guides 2 at the sides of the horn the entire surface of the portion *a* is unbroken, and it will be seen that for operating as herein described in putting on a shoe it is essential that the portion *a*, which slides with the foot in entering the shoe, should be within or on the concaved side of the portion *b*, which is placed in the shoe on the first instance.

I claim—

1. In a shoe-horn, the combination of one part adapted to enter the heel of the shoe, and provided with guides at its edges, with another part on the concave side of the former, arranged to slide within the said guides, substantially as and for the purpose set forth.

2. In a shoe-horn, the combination of one part provided with a heel-engaging hook with another part arranged to slide telescopically into the first-mentioned part, substantially as described.

3. The combination of the part *a*, provided with a stop-projection, *c*, of the part *a'* on the concave side thereof, provided with guides at its edges for the part *a*, and the groove to receive the said stop-projection, substantially as and for the purpose described.

In testimony whereof I have signed my name to this specification in the presence of two subscribing witnesses.

JESSE M. BROWN.
